UNITED STATES PATENT OFFICE.

CHARLES H. GUNN, OF OAKLAND, CALIFORNIA.

FLUSH VALVE.

Application filed November 27, 1922. Serial No. 603,521.

To all whom it may concern:

Be it known that I, CHARLES H. GUNN, a citizen of the United States, residing at Oakland, county of Alameda, State of California, have invented certain new and useful Improvements in Flush Valves; and I do declare the following to be a full, clear, and exact description of the same, reference being had to the accompanying drawings, and 10 to the characters of reference marked thereon, which form a part of this application.

This invention relates to toilet-flush systems, and is particularly intended as an improvement of that type of device shown in 15 my co-pending application for patent on "toilet flush," filed September 5th, 1922, under Serial No. 586,308.

The principal object of the present invention is to simplify the construction 20 shown in the above identified application, by doing away with numerous parts without altering the principle of operation or reducing the efficiency of the device.

I have also provided a valve operating 25 means which is simpler and more convenient to operate than that of the first type, and have arranged that the valve member itself may be very quickly and easily removed without disturbing the control or operating mechanism.

A further object of the invention is to produce a simple and inexpensive device and yet one which will be exceedingly effective 30 for the purposes for which it is designated.

These objects I accomplish by means of 35 such structure and relative arrangement of parts as will fully appear by a perusal of the following specification and claims.

In the drawings similar characters of 40 reference indicate corresponding parts in the several views:

Fig. 1 is a side elevation of a toilet showing my improved flush valve and tank installed in connection therewith.

Fig. 2 is a sectional elevation of the tank and the connected parts.

Fig. 3 is a top plan view of the float-valve with its guide means.

Fig. 4 is a detached view of the valve-raising stem.

Referring now more particularly to the characters of reference on the drawings, the numeral 1 denotes the flush tank or reservoir, of desired shape and size and substantially air tight, with which is connected a water supply pipe 2.

Screwed into the bottom of the tank is a special T-fitting 3, the upper end of said fitting having an orifice 4 communicating with the tank and of smaller diameter than the interior of the fitting. The metal surrounding said orifice is raised to form a flange or rim 5 which serves as a seat for a valve-pad 6 of rubber or the like, which is fitted into the lower end of a hollow cylindrical and preferably metallic float 7, said pad being held in place by a screw 8 whose head projects downwardly into the orifice 4 when the valve is seated.

The lower end of the member 3 is adapted 70 to be connected to the usual forms of flush pipe 9 leading to the toilet bowl 10.

Screwed into the upper end of the member 3 about the float are guide rods 11, which extend upwardly to a point adjacent the top 75 of the tank, and are there connected together and held in spaced relation by a ring 12. The bore of this ring is of sufficient size to enable the float to pass therethrough, so that it may be withdrawn from the tank when desired upon the removal of a plug 13 fitted in the upper end of the tank above the ring.

Formed with the fitting 3 in vertical alignment with the orifice 4 are sleeves 14, one being above and below the side portion or 85 chamber 3^a of the fitting 3, these sleeves forming guides for a vertical rod 15 substantially the same size as the opening 4, the upper end of which rod is preferably provided with a rubber or other resilient head 90 16 which is adapted to abut against the screw-head 8.

The possible vertical movement of this rod is limited in a downward direction by reason of a shoulder 17 thereon which normally abuts against the upper face of one of the sleeves 14, while movement in an upward direction is limited by an adjustable nut 18 on the lower end of the rod which is adapted to abut against the under face of 100 the lower sleeve 14.

The rod 15 is provided with a vertical slot 19 intermediate the guide sleeves, in which slot, centrally of its ends is located a transversely disposed roller 20 mounted on a pin 105 21 fixed in the rod.

An arm 22, fixed on a horizontal shaft 23 which is turnably mounted in the member 3^a transversely thereof, and is parallel to said roller, has a forked portion 24 at 110 its free end, which portion projects into the slot 19 and straddles the roller.

A handle-lever 25 is fixed on the shaft 23 outside the member 3 and extends toward and alongside the bowl 10, the normal position of this lever, when the rod 15 is lowered 5 and the valve is seated, being at a slant about 5° below a horizontal line.

A removable cap or plug 26 is fitted in the outer end of the member 3^a so as to aid in placing or removing the arm 22.

10. The tank is preferably supported by the floor by means of a stanchion 27 screwed into a boss or socket 28 formed with and on the underside of the member 3^a.

15. A lug 29 is also provided on the upper end and back face of the tank, to receive a lag screw 30 extending into a wall-joist.

In assembling the device, the fitting 3, with the floor, guide rods, operating lever and all other parts, are assembled as a complete unit, the guide rods 11 being then slipped up into the orifice in the bottom of the tank into which the fitting 3 is screwed prior to the accomplishing of the latter operation.

25. In the operation of the device, the pressure of the water on the float 7 when the tank is full holds the float seated.

When it is desired to flush the tank, the lever 25 is raised for its full travel, as 30 governed by the possible movement of the rod 15, which as will be evident is raised at the same time. This raising of the rod causes the float to be raised from its seat, and it will then float to the top of the water 35 in the tank, descending as the water level is lowered.

The float is prevented from being prematurely drawn back into its seat with the inrush of water through the orifice 4 before 40 said float has a chance to rise to the surface for two reasons. First, because the movement of the rod is intentionally so great that the float when raised as high as possible by said rod is above the main suctional influence of the water pouring through the orifice 4. To aid in minimizing this influence, the lower corners of the float are cut away on a slope, so as to reduce the under-face area thereof. Secondly, the 45 rod 15, being as before stated, about the same size as the opening 4, said opening is practically closed by the rod when the latter is raised, so that but very little water can then enter said opening, and the suctional influence of the water is very slight.

The rod, having functioned to raise the

valve or float will instantly drop to its normal position both by reason of the water pressing thereon and because the length of the lever 25 and its weight are such as to 60 cause said lever to drop as soon as the operator releases the same.

As the water in the tank is emptied, the float, of course descends, until it is brought within range of the suctional influence of 65 the outpouring water, when it will be drawn to its seat, and once seated, will remain there until again raised by the operating rod 15.

From the foregoing description it will be readily seen that I have produced such 70 a device as substantially fulfills the objects of the invention as set forth herein.

While this specification sets forth in detail the present and preferred construction of the device, still in practice such deviations from such detail may be resorted to as do not form a departure from the spirit 75 of the invention, as defined by the appended claims.

Having thus described my invention, what 80 I claim as new and useful and desire to secure by Letters Patent is:

1. A flush valve structure comprising a hollow fitting adapted to be interposed between the lower end of a tank and a toilet bowl, a float valve to seat adjacent the upper end of the fitting, a vertical rod in the fitting below the valve and adapted to engage and raise the same, means for raising the rod, guide sleeves in the fitting for the latter, a 90 shoulder on the rod resting on the upper face of one sleeve when the rod is in its lowermost position, and an adjustable nut on the rod and adapted to abut against the under face of the sleeve when the rod 95 has been raised a predetermined amount.

2. A flush valve structure comprising a hollow fitting adapted to be interposed between the lower end of a tank and a toilet bowl, a float valve to seat adjacent the upper 100 end of the fitting, a vertical rod in the fitting below the valve and adapted to engage and raise the same, a pin extending transversely of the rod, an arm slotted from one end engaging the pin, a shaft on which 105 the arm is mounted journaled in the fitting parallel to the pin, and a removable plug in the fitting beyond the shaft and on the side thereof away from the rod.

In testimony whereof I affix my signature.

CHARLES H. GUNN.
